FUEL PUMP

Max Dach, Flushing, N. Y.

Application September 17, 1942, Serial No. 458,657

2 Claims. (Cl. 103—203)

This invention relates to fuel pumps for internal combustion engines, and more particularly to an improvement therein which may be embodied in the conventional pump or in an attachment therefor.

It is well known that fuel, such as gasoline, used for internal combustion engines vaporizes readily and quite often vaporization prevents the pump from operating properly. Excess pressures forming in the line prevent the pump from functioning efficiently, as does vapor accumulating in the pump with no outlet to escape. Means have been heretofore provided to relieve excessive vapor pressures on the pressure side of the pump by means of attachments. One of the purposes of this invention is to relieve pressures and vaporization on both sides of the pump, and especially on the suction side of the pump where they occur as often as on the pressure side.

In the present-day pump vapors are often trapped between the intake and outlet valves, and it is the purpose of this invention to provide a pump in which the vapors will not be trapped within the pump but will vent themselves through a relief valve on one side and be transferred either to the carburetor bowl or returned to the tank, and on the other side the vapors may vent themselves through the carburetor needle valve.

An object of the invention is therefore to provide a pump in which the areas where vapors are apt to be trapped are so constructed as to allow the vapors to vent themselves automatically.

A further object is to provide a more suitable valve which will increase the efficiency of the pump.

With these and other objects in view, which will become more apparent as the description proceeds, reference is had to the accompanying drawing, in which—

Fig. 1 is a sectional elevation showing my invention embodied within a more or less conventional fuel pump;

Fig. 2 is a sectional elevation showing my invention embodied in an attachment for a conventional fuel pump.

Referring to Fig. 1, the pump 10 is provided with the usual pump chamber 11 about a diaphragm 12, the outlet valve 13 and inlet valve 14 leading from the filter bowl 15. These parts operate in the customary manner, in which the diaphragm 12 on the down or suction stroke closes the outlet valve, opens the intake valve, and draws fuel from the tank 16 through the line 17, passage 18, filter bowl 15, and the intake valve

14. The diaphragm 12 is operated by the rocker arm 19 engaging the cam shaft 20. On the pressure stroke the pressure from the diaphragm 12 closes the intake valve 14, opens the outlet valve 13, and forces the fuel through the line 21 through the carburetor 22.

In the conventional pump difficulty has been experienced with vapors rising from the filter bowl 15 and the chamber 11 forming in the passage 18 and in the area 25 and 26, thus forming a vapor lock which prevents the efficient operation of the pump. The head of the filter bowl is usually provided with a depending tube 30 which extends below the top of the bowl to support the screen 29. I provide an opening 31 in the passage 18 leading directly into the bowl and construct the head 32 of the bowl with an additional opening 33 leading to the valve 34 positioned by the spring 35. If the valve 34 is made of Neoprene, or other material which will not float in gasoline, the spring 35 is not necessary since the valve will automatically seat itself unless the vapor pressures are such as to open it. Above the valve 34 is a restricted passage 36 which leads to the line 37 which may go either to the carburetor float chamber 38 or back to the tank. While I have shown the valve 34 as a flat valve in Fig. 1, a ball valve (as shown in Fig. 2) made of Neoprene or other suitable substance, may be used.

It will be noted that I have eliminated in the pump chamber 11 the usual shoulder or boss contained in the conventional pump, so that the bottom of the passage 27 leading to the outlet valve 35 is flush with the top of the chamber to enable vapors which may form in the top of the chamber 11 to pass out through the outlet valve and to be vented by the carburetor needle valve.

As the pump is operated, any vapors or built-up pressure in the area 18 will pass upwardly through the opening 33, and if the fuel is heated considerable pressure is built up to force open the valve 34 to allow the vapors to pass through the pipe 37 back to the tank, or to the float chamber of the carburetor. The valve 34 may be controlled so that no more fuel can escape than the engine consumes at low speed and the restricted passage 36 will accomplish the same result. While theoretically the pump on the suction stroke will cause the intake valve 14 to open and the relief valve 34 to close, and while on the pressure stroke it will cause the valve 14 to close, as a practical matter there is a slight lag between the pressure and suction strokes and a period during which the intake valve remains open until

the force of the pressure stroke is sufficient to close it. This sets up a slight back wash in the filter bowl 15, as the result of which there is a point where a certain amount of pressure is exerted against the valve 34 irrespective of whether or not pressure has been built up in the filter bowl by vapors. It follows, therefore, that the valve 34 will open slightly each time the pump changes or has a tendency to do so. In order to insure this action, a slight hole may be drilled in the valve 14 to create an artificial back wash.

In the attachment shown in Fig. 2, the housing 50 is provided to screw into the end 51 of the fuel pump 10 connecting the passageway 53 with the line 54 from the gas tank. An opening 55 leads to the valve seat 56 and a spring-controlled valve 57, which may be a Neoprene ball or a flat valve, as shown in Fig. 1. An opening 58 is made between the passageway 53 and the filter bowl 15 to allow vapors to pass into the passageway.

Beyond the valve 57 is a chamber 60 closed by a plug 61 which has an opening 62 connecting with the line 63 leading to the float chamber of the carburetor or back to the tank. The plug 61 has depending walls 64 forming a valve seat 65 at the lower end thereof. As vapors build up pressure in the line or in the filter bowl, the ball 57 will be pushed upwardly against the seat 65 to allow said vapors to pass into the chamber 60. In the event no pressure is built up, this action will take place on the pressure stroke of the pump. Before the inlet valve 14 is closed on the suction stroke of the pump, the ball 57 will be reseated and the vapors allowed to pass through the passage 62 in the line 63.

It will be appreciated that the form shown in Fig. 2 is adaptable to pumps now in use.

Where the operation of the intake valve is per-

fect and no back wash occurs in the change from the suction to the pressure stroke, the valve seat may be notched or a small passageway drilled in the pump to create a definite backwash within the filter bowl.

It will be appreciated that slight modifications may be made in my device to accommodate it to various types of pumps without departing from my conceptional idea which includes the use of a 10 relief valve to prevent vapors forming in the suction end of the fuel line and to be operated automatically by the action of the pump, and that the pump chamber and filter bowl are so designed that rising vapors will not be trapped by 15 the structure of these elements and may find their way automatically to the pressure outlet valve and to the relief valve.

I claim:

- 20 1. The combination with a fuel pump having an inlet and an outlet valve and a filter bowl on the suction side of said pump with a passage leading to said filter bowl from a feed line, of a supplemental valve between said filter bowl and said feed line communicating with said passage, 25 said valve communicating with a line adapted to carry off vapors forming on the suction side of said pump.
2. A fuel pump comprising a pump chamber, a diaphragm in said chamber, and means for 30 operating said diaphragm, an outlet valve, the bottom of said outlet valve being on a level with the top of said chamber, an inlet valve, a filter bowl communicating with said inlet valve, a passage leading from the fuel line into said filter bowl, a supplemental opening between said passage and said fuel bowl, and a relief valve positioned between said fuel line and said filter bowl.

MAX DACH.
